CASH REGISTER

Charles W. Green, Ilion, N. Y., assignor, by
mesne assignments, to The National Cash
Register Company, Dayton, Ohio, a corporation
of Maryland

Original application April 13, 1927, Serial No.
183,392. Divided and this application June 30,
1928, Serial No. 289,348

7 Claims. (Cl. 235—137)

This application is a division of my co-pending application, Serial Number 183,392, filed April 13, 1927 (now Patent No. 1,874,285, issued on August 30, 1932), to which reference may be had for a more complete description of the cash register to which the present invention has been applied. While the improvements set forth in this application are shown in conjunction with a particular type of cash register as illustrated in the parent application their utility is by no means limited to this specific embodiment. The improvements are of such a nature that they may be applied in various modifications to many other types of cash registers and accounting machines.

A broad object of the present invention is to provide an improved transfer or carrying mechanism whereby, as the result of the completion of a rotation of any totalizer wheel of a lower order, the wheel of next higher order will be turned through one step.

A more specific object is the provision of an improved mechanism for placing normally ineffective transfer pawls in condition for carrying; as well as to provide a novel and efficient means for actuating such pawls to impart carrying movement to the appropriate totalizer wheels.

A further object of the invention consists in providing for resetting to zero of the totalizer by turning the totalizer wheels in the same direction as that in which they are rotated for addition; with provisions for restoring to normal position the transfer devices that are tripped by the resetting of said wheels.

An additional object is to provide a novel and effective guiding means for certain transfer elements; which guiding means, moreover, is operable to effect restoration of said elements to normal during resetting operations.

Another object is the provision of an improved means for positively preventing over-carrying of the totalizer wheels.

With these and incidental objects in view the invention consists of certain novel features of construction and combination of parts, the essential elements of which are set forth in the appended claims and a preferred form of embodiment of which is hereinafter described with reference to the drawings which accompany and form part of this specification.

Of said drawings:

Fig. 1 is a top plan view of the machine of my parent application aforesaid, in connection with which the present invention is illustrated; the cabinet of said machine being cut away to show

the arrangement of the mechanism located within.

Fig. 2 is a vertical sectional view of the machine taken on line 2—2 of Fig. 1. This view shows particularly the differential and totalizing devices and the means whereby they can be brought into and out of cooperative relationship.

Fig. 3 is a top plan view of a number of the elements associated with the resetting mechanism.

Fig. 4 is a view in side elevation of a portion of the mechanism utilized in connection with the resetting operations.

Fig. 5 is a vertical sectional view of the totalizer showing the transfer mechanism.

Fig. 6 is a top plan view showing the relation between the transfer devices and the denominational elements of the totalizer.

Fig. 7 is a view in side elevation showing the position of the transfer elements after the totalizer wheels have been brought to zero.

Fig. 8 is a detail view of certain parts which serve to restore the transfer pawls during resetting.

Fig. 9 is a detail view of the lowest order transfer operating cam.

Keys, key coupler, and full stroke device

Described in general terms the illustrative machine comprises keys 32 divided into groups (Figs. 1 and 2) one group for each denominational order, such as, for example, units, dimes and dollars. Obviously, more amount keys could be provided if more groups or higher denominational orders were desired, so as to increase the capacity of the machine. A special key 31 is also provided and is designated as the "No sale" key, the primary function of which is to release the cash drawer for the making of change.

As shown in Figs. 1 and 2, the amount keys 32 and the "No sale" key 31 are pivoted upon a shaft 40 supported by the side plates 20 and 21. In order to provide a suitable bearing for the shaft 33, since the side plates are of relatively thin material, these plates 20 and 21 are punched and drawn outwardly at the proper points so as to form portions 34 (Fig. 1) in the form of collars, the internal bore being substantially that of the diameter of the key supporting shaft 33. By the construction just described suitable journalling points are provided for the said support shaft. Lateral movement of the shaft 33 is prevented by the cabinet 27, the sides of which are adjacent the ends of said shaft.

The amount keys 32 and "No sale" key 31, which carry at their respective outward ends or

front portions thereof suitable key cups bearing indicia designating the nature of the keys, play in the vertical slots 28 (Fig. 2) formed in the cabinet. At their rear ends the keys are guided by slots 35 formed in a plate 36 secured to the cross bar 25 by screws 37.

Extending between the side plates 20 and 21 and resting upon the rear end of the keys is a key coupler 39. The key coupler is pivotally supported by means of plates 40 and 41 (Figs. 1 and 2) attached to the key coupler and which are suitably apertured to receive a transverse shaft 42 located approximately above the aforementioned shaft 33. Said shaft 42 is supported by the side plates 20 and 21 in a manner similar to the shaft 33. It will be obvious that when the forward ends of the keys are depressed the key coupler 39 will be rocked clockwise so that its rearward end will enter the notches 38 of the depressed keys. The purpose of such key coupler mechanism is well known in the art and need not be discussed herein.

To insure a complete performance of the started registration before a second operation can subsequently be effected, any suitable full-stroke mechanism may be employed (such, for example, as that disclosed in my parent application hereinbefore referred to). Various full-stroke devices are well-known in the art and need not be here discussed.

Differential and totalizer device

As is shown in Fig. 2 each amount key 32 is formed with an upwardly extending portion 46 adapted to engage with a respective denominational differential frame which is pivoted upon the shaft 42. Each differential frame comprises the side members 47 (see Figs. 1 and 2) integrally joined by a cross bar or bail 48 which normally stands over the extending portion 46 of the keys of each bank. The portions 46 are graduated so that the keys of each bank will impart to the associated differential frame varying degrees of movement, depending upon the values represented by said keys. Secured to each frame is a segmental rack 50 adapted to operate an associated totalizer element of corresponding denomination. It will be understood, therefore, that a differential frame 48 and a segment 50 are associated with each group of nine keys 32 of each decimal order.

The registering mechanism, whereby items determined by the keys are accumulated to furnish a total of the amounts entered, is in the main carried by a frame comprising side plates 67 and 68 (Figs. 1, 2, 5 and 6) which are tied together at their rear ends by a cross rod 69 and bifurcated at their lower portions to engage the shaft 42. The frame is held in position by a shaft 70 journaled in the side frames 20 and 21 and passing through circular apertures formed in each of the side members 67 and 68.

The totalizer proper comprises a series of registering wheels 75 loosely mounted on a shaft 74. Attached to the wheels corresponding with the segments 50 are pinions 76 adapted to mesh with said segments. Included in the series of wheels 75 are a number of wheels of higher order than those corresponding with the segments 50, which higher order wheels are operable to receive the overflow of accumulations on the lower order wheels whereby totals exceeding the capacity of said lower order wheels may be accumulated. The shaft 74 is carried by a frame which consists of side members 71 and 72 integrally con-

nected by a cross member 73 and pivoted within the stationary frame 67, 68 by short pins 77 (Fig. 6) passing through the side members 67 and 68 and into the side members 71 and 72 of the totalizer frame. These are the pivots about which the totalizer frame is adapted to be rocked during the initial depression of the keys so that the totalizer pinions 76 will be immediately rocked into engagement with the actuating segments 50, the latter being then differentially operated under control of the keys so that at the extreme end of the depression of the keys a corresponding amount will have been entered into the totalizer. Upon the return movement of the keys the totalizer pinions will be disengaged from the segments, thus permitting the latter to return to their normal positions without affecting the entry made upon the totalizer. The mechanism for effecting the above-mentioned rocking of the totalizer frame will now be described.

Totalizer engaging mechanism

Loosely mounted upon the shaft 42 and slotted so as to engage the key coupler 39 is a segment plate 78 (Figs. 1, 2 and 6) which extends vertically in a plane adjacent the side frame 67. The segment plate at its upper end is provided with bent over lugs 79 and 80 and carries a supporting collar 81. Pivotally mounted by means of a pin fitting in the collar 81 is a plate 82 provided with stop shoulders 83 and 84 which are adapted to cooperate with the lug 79. A switching cam plate 85 is attached to the plate 82 by suitable means such as a pair of rivets. A spring 86 (Fig. 2) connected between the segment 78 and the plate 82 normally retains the parts in the position shown in the above figure. The shaft 74 mounted in the totalizer frame is adapted to be engaged by an open ended slot formed in a member 88 which is pivoted at 89 to the supporting frame member 67. The rearward end of the member 88 carries a pin 90 normally resting upon the lug 80 and the member 88 is also provided with a pair of stop shoulders 91 and 92 adapted to cooperate with a pin 93 carried by the frame member 67.

In the position shown in the drawings (Fig. 2) it will be noted that the totalizer frame is normally locked and any downward movement, accidental or intentional, will be prevented by the cooperation of the pin 93 with the lug 80 while upward movement is prevented by the shoulder 92 engaging the pin 83. During the operation of the machine the key coupler 39 will rock the plate 78 clockwise and the initial movement will permit the totalizer frame to be rocked by the member 88 so that the totalizer pinions 76 may engage their related segmental racks since at this time the pin 90 will pass between an inclined portion 94 of the lug 80 and the adjacent edge of the switching cam plate 85. Continued rocking of the plate 78 will positively cam the totalizer frame by the action of cam plate 85 to carry the totalizer elements into their lower or engaged position, this action being assisted by the weight of the totalizer frame. During the continued clockwise movement of the plate 78 (Fig. 2) the segments will be moved differentially in the manner hereinbefore described, and during this time the pin 93 will contact with the underside of the cam plate 85 to hold the totalizer frame positively locked against upward movement, thus insuring engagement of the totalizer pinions with the racks throughout the down-stroke of the keys even though the keys 75

should be operated quickly and violently. When the plate 78 has rocked far enough to carry the pivot point of the cam 85 past the pin 90 the cam will rock clockwise against the tension of the spring 86 without disturbing the position of the pin. At a certain point in the operation the pin 90 will be completely disengaged from the cam plate 85 thus permitting the spring 86 to again rock the plate to its normal position. At 10 substantially the same time the pin 90 will pass beneath the lug 79 to still prevent any movement of the pin and plate 88. This condition is obtained at the extreme end of the down-stroke of the keys at which time the totalizer is still 15 positively locked in the position in which the pinions are engaged with the segment racks.

At the beginning of the return movement of the plate 78, which is contemporaneous with the return stroke of the keys, the rearward camming edge of the cam plate 85 will cam the pin 90 upwardly thus positively rocking the totalizer frame to disengage the pinions from the segment racks. During the remainder of the return 20 movement of the segment 78 the pin 90 will ride over the upper edge of the cam 85 which will guide the pin 90 over the lug 80 until the pin again occupies the position shown in the drawings. It will be understood that the totalizer frame is also locked against movement during 25 the return stroke of the keys.

In rapid operations of the machine there may be danger that the spring 86 will not act quickly in rocking cam plate 85 to insure the proper return of the pin 90 along the upper edge of the cam plate upon the return movement of the plate 78. To prevent misoperations which would result if the pin 90 did not describe the proper path under these circumstances the shoulder 34 of the plate 82 which carries the cam 85 is bent 35 outwardly to cooperate with the pin 90 as the plate 78 reaches its extreme forward limit of movement so that if the spring 86 does not rock the plate 85 the pin contacting with the lug of shoulder 84 will positively force said plate 85 to the proper position. It should be noted that the pin 90 at this time is held down by the lug 79 and can, therefore, have a very positive action 40 on the sloping overturned portion 84. The subsequent riding of the pin 90 over the rear beveled portion of cam plate 85 will thus always be insured. While this device is simple it is an effective and adequate remedy for misoperations 45 which might occur without it.

Transfer mechanism

The transfer mechanism employed for the wheels above the units order is of the type in which the several orders are independently and successively actuated and it is operated upon the 50 return stroke of the keys at which time the totalizer pinions are out of mesh with their respective actuators.

Each totalizer wheel carries a transfer pin 115 (Figs. 5, 6, and 7) which is in the plane of an extension 116 of a transfer trip pawl 117 provided with a stepped shoulder 118. The trip pawls 117 are urged in a counter-clockwise direction by springs 116' shown in broken lines in Fig. 7. The transfer pawls 120 are urged 55 counter-clockwise (Figs. 5 and 7) by coil springs 128 so that normally a lug 121 formed thereon rests upon the shoulder 118. Each transfer pawl is pivotally mounted upon a related arm 122 all of which are journalled on a shaft 123 carried by 60 the end portions 124' of the main spacing

bar 124 which is securely fixed between the side plates 71 and 72 of the totalizer frame. Shaft 123 is in direct alignment with pivot pins 117. When a totalizer wheel of a lower order makes a complete revolution the pin 115 will urge the trip pawl 117 forwardly thereby disengaging the lug 121 from the shoulder 118 and permitting the spring 128 to urge the transfer pawl 120 downward until the bottom edge of the transfer pawl rests upon the spacing bar 124. At 10 this time the engaging end of the transfer pawl will be brought into operative engagement with a tooth of a ratchet wheel 125 (Fig. 7) attached to the next higher order wheel so that when the transfer pawl is moved rearwardly cooperation 15 of the pawl with the ratchet wheel will advance this wheel to effect the necessary transfer. In so doing the transfer pawl will also be raised due to the camming action of the next ratchet tooth so that the lug 121 will again rest upon the 20 shoulder 118.

When a pawl 117 is tripped or forced forward by a transfer pin 115 as above described, the transfer pawl 120 will be released and will be drawn downward by the coil springs 128, but if 25 they should move downward too slowly or by any means become stuck in their elevated positions they are positively forced downward by pins 1171 (Fig. 7) carried by the trip pawls and adapted to engage the upper edge of the transfer pawls. 30

The tail of the pawl 120 is bent to form a lug 119 which is adapted to cooperate with the forward edge of the related arm 122, and is provided for the purpose of preventing said pawl from being out of engagement with the ratchet teeth at 35 the end of the extreme rearward travel of said pawl with the result that overthrow due to a too rapid transfer operation is prevented.

The upper edge of the transfer pawl 120 is preferably notched as at 1200 (Fig. 7) so that at the 40 extreme end of the transfer operation the pin 1171 will overlie the notch 1200. This permits lug 119 to function as an overthrow preventer alone but if so desired the notch 1200 and lug 119 may be dispensed with so that pin 1171 coacting 45 with the upper straight edge of the pawl 120 will prevent overthrow. In some instances it may be desired to use both the pin 1171 and lug 119 to prevent overthrow.

The means whereby the transfer pawls are successively actuated so as to effect the necessary transfers comprises, as best shown in Fig. 5, a series of links 126 each connected to a related arm 122 and slotted so as to engage and rest upon an oscillating transfer shaft 97 mounted between and 50 supported by the two side support plates 67 and 68. The oscillatory movement of the transfer shaft 97 just mentioned is derived by the following means:

Located adjacent the support frame 68 is a 55 plate 93 (Figs. 1 and 5) pivotally mounted upon the shaft 42 and having a lower extension 94 engaging the key coupler 39. The upper portion of the plate takes the form of a rack 95 adapted to drive a gear 96 which is attached to the shaft 65 97. Consequently, during an operation of the machine, the key coupler will rock to similarly rock the plate or segment 95 thereby imparting an oscillatory movement to the transfer shaft 97.

Upon the shaft 97 are secured a plurality of 70 transfer cams 127 which are spirally arranged so as to actuate the links 126 of the different denominational orders seriatim. Each cam 127 is in the plane of a pin 129 carried by its associated link 126. It will be obvious that during the down- 75

ward stroke of the keys the transfer shaft 97 will first be rocked counter-clockwise as previously described, and by the cooperation of the cams 127 with the pins 129 the several links will be successively elevated; the links 126 during such rocking movement being guided by the cooperation of concentric edges 130 of the links with the shaft 97 until the cams clear the pins whereupon the links will drop to their normal positions. During the return stroke of the keys the cams 127 will engage the opposite sides of the pins 129 thereby forcing the links forwardly, the latter being guided in their movements by the slotted portions above fingers 131 engaging the shaft 97. In this manner each of the transfer pawls 120 will be actuated and those that have been tripped will effect transfers. When the cam 127 clears the pin 129 the coil spring 128 connected between the arm 122 and its associated transfer pawl will return the parts to normal (Fig. 5). It will be noted that as the cam 127 moves the link 126 forwardly to force the transfer pawl rearwardly the ends of the spring 128 will be brought together thus storing up additional energy in said spring and this energy is released when the cam 127 leaves the pin 129. Since the link 126 by moving the arm 122 stores up energy in spring 128 this energy will be dissipated to return arm 122 and link 126 when the latter is released from the cam 127. When the link 126 is released the energy in the spring 128 will tend to rock the pawl 120 counter-clockwise, but since the pawl already contacts a stationary member the energy will be used to rock arm 122 clockwise thus forcing arm 126 rearwardly and pawl 120 forwardly.

It will be observed from what has just been stated that the upward movement of the links 126 is produced by the cams 127 during the downward movement of the keys, and that after each cam 127 is entirely disengaged from the related pin 129 the weight of the link is depended upon to restore it to its lower position where it rests upon the shaft 97 so that shortly after this the reverse movement of the cam 127 will force the link forwardly to effect a transfer. In rapid operations of the machine the weight of the member 126 may not be sufficient to restore it to its normal position prior to the return movement of the cam 127 so that if the links 126 should be held by frictional forces the finger portion of the link indicated by the reference character 131 (Fig. 5) would engage the rear portion of the transfer shaft 97 and thereby prevent further operation of the keys. In order to prevent such misoperations a tensioning device which is common to the links 126 is provided and (as shown in Figs. 5 and 6) comprises a bail member 132 which is loosely pivoted upon the tie rod 69 and is urged clockwise by a spring 133 so that bent extensions 134 thereof cooperate with the upper rearward edges of all the links 126. As will be observed in Fig. 6 a plurality of these extensions is provided to cooperate with all of the links but normally the extensions are slightly above the links and are held in this position by means of a lug 135 integral with the member 132 contacting a portion of said frame 67.

It will also be observed in Fig. 9 that the cam 127 associated with the transfer elements between the units and dimes denominational orders is of different contour than the other cams in that a considerable portion of its outer periphery is concentric with respect to the shaft 97 so that at the beginning of the operation of the shaft the high concentric portion of this cam will almost

immediately coact with the pin 129 of the related link 126 and will raise the latter and hold it elevated for a considerable period. Since one of the extensions 134 coacts with the upper side of this link it will rock the member 132 upwardly against the tension in the spring 133 and will retain it in this position until the operated key reaches close to the end of its downward stroke. This construction prevents a "ratcheting" effect which would otherwise occur as the pins 129 of the several links 126 successively drop from the high portions of their related cams 127. When the pin 129 leaves the outer concentric part of the cam 127 of the lowest denominational order, the member 132 is released, so that the spring 133 will urge it downwardly and if one of the links 126 should be held elevated due to friction the related extension 134 will urge it downwardly to its normal position. This insures the restoration of the links to their normal positions prior to their forward movements and it will be apparent that by this means the danger of the portions 131 coacting with the shaft 97 will be minimized if not altogether obviated.

The spring 133 is tensioned only during the down stroke of the keys when the most power is available. Since the projections 134 are a slight distance above the links 126 during the return stroke of the keys the spring 133 will have no action on the arms 126 and will, therefore, not place any additional load on the machine at a time when the available power is least.

It will be observed that a transfer pawl and related devices are provided for all of the wheels of denominational orders higher than the units and the several orders from lower to higher are operated successively so that at the end of an operation of the machine the transfer pawls will all have been operated and by thus completing the necessary transfers the totalizing wheels will indicate the true total sum registered.

Resetting devices

Resetting in the present machine is accomplished in a manner generally known, that is, by manually rotating the shaft 74 so that the square shoulder of a groove 205 (Figs. 3, 5, and 7) formed therein will cooperate with resetting or pick-up pawls 206 carried by the totalizer elements. Thus, when the shaft 74 is rotated in the proper direction the groove therein will cooperate with the pick-up pawls 206 in whatever positions the latter happen to be and carry them and the connected totalizer elements to their zero positions. It will be noted that the relation between the groove and pawls is such that the wheels of the totalizer are restored by rotation of the shaft 74 in the same direction in which they are driven by the actuating segments 50, so that by this construction the numeral wheels are free to rotate about the shaft 74 in adding operations without causing any movement of the shaft. As best shown in Figs. 1, 3, 4, and 6, the shaft 74 has connected to it a resetting bar 207 which fits loosely in an aperture formed in a bracket 208 attached to the side frame 21. The connection between the bar 207 and the shaft 74 is formed by inserting the bar in a slot in the shaft and passing a pin through them thus providing a swivel construction and it is such that in the normal position of the parts the totalizer is free to be rocked into and out of mesh with the racks. The cabinet 27 and side plate 21 are both provided with apertures 203 (Fig. 3) through which the stem of a resetting key 209 is adapted to be

inserted so that by the cooperation of a slot 210 formed in the end of the key 209 with the end of the bar 207 the shaft 74 may be rotated to reset the totalizer elements.

5 Under normal conditions, that is when the machine is in its registering condition, the apertures may be closed by any suitable means. For example, there may be employed a plate 198 (Fig. 4), movable into and out of range of the 10 apertures by any suitable means. Such means forms no part of the invention claimed herein, and need not be here described, although one form thereof is shown in my parent application above referred to.

15 As previously stated, in resetting operations the totalizer elements are driven by the shaft 74 in the same direction that the actuators drive them. It will, therefore, be apparent that during the resetting operations the trip pins 115 20 carried by the wheels will cooperate with the trip pawls 117 and trip the latter as in adding operations. For this reason it is necessary to restore the tripped transfer pawls to their normal inactive positions, since otherwise irregular transfers 25 would be effected during the first subsequent operation of the machine. The shaft 74 (as best shown in Fig. 8) has attached thereto a cam 214 which is in the plane of one arm of a bell-crank 216 (Figs. 6 and 8) pivoted at 2169 on the frame member 58. The other arm of the bell-crank 216 carries a pin 217 engaging a bifurcation in an arm 218 attached to a shaft 219 journaled in ears integral with the tie bar 124. A coil spring 220 acting between a fixed stud and the pin 217 30 urges the arm 216 against the periphery of the cam 214. The shaft 219 is provided with a plurality of slots 221 (Figs. 6 and 7) adapted to receive and guide the transfer pawls 120 as well as to restore them after they have been tripped during a resetting operation.

40 The operation of the foregoing mechanism may now be pointed out. When resetting commences by manual rotation of the inserted resetting key a counter-clockwise rotation of the shaft 74 (Fig. 5) will cause the groove 205 to pick up the variously positioned pawls 206 to restore the totalizer elements. During this counter-clockwise rotation of the shaft 74 the periphery of the cam 214 will cooperate with the arm 216 and gradually rock the latter and through the connections previously described, comprising the pin 217 and arm 218, will rock the slotted shaft 219 clockwise (Figs. 7 and 8). This rotation of the shaft will carry the slots 221 away from the transfer pawls 120 and will present the outer periphery of the shaft to these pawls tending to rock them slightly upwardly, the lug 121 at this time coacting with and sliding along the upper rearward edge of the trip pawl 117. When the highest part of the cam 214 contacts the arm 216 the transfer pawls will be elevated to their highest positions and the continued counter-clockwise rotation of the shaft 74 (Fig. 8) will reversely rock the bell-crank 216 and the shaft 219 will rock counter-clockwise back to normal thus permitting the transfer pawls 120 to be lowered. The above described operation of the pawls 120 is merely an incident to the construction and relation between the parts, as it has no particular function. 55 This operation results from the fact that the shaft 74 receives two movements, first counter-clockwise, and then clockwise back to normal. The clockwise movement of shaft 74 performs the necessary function of restoring the tripped transfer pawls. At substantially the end of the coun-

ter-clockwise rotation of the shaft 74 all of the totalizer elements will be passing from their "9" to their "0" positions at which time the trip pins 115 will cooperate with the trip pawls 117 releasing all the transfer pawls 120 in the same manner that they are released during a regular transfer operation.

5 At this time rotation of the shaft 74 will be stopped by the cooperation of an integral extension 222 (Figs. 1 and 4) of the bar 207 with a pin 223 carried by the bracket 268. Reverse rotation of the shaft 74 will, in the form of embodiment shown, restore the tripped transfer pawls; but this operation will have no effect on the totalizer elements, which are at this time 15 in their zero position. As the shaft 74 is thus rotated reversely, or in a clockwise direction (Fig. 8), it will rock the shaft 219 first clockwise (Fig. 7) and since at this time the transfer pawls have been released so that their lugs 121 20 are disengaged from the shoulders 118 and the pawls rest upon the supporting tie bar 124, the bottom of the slots 221 will have a camming effect upon and will elevate the transfer pawls until the lugs 121 are above the shoulders 118. At 25 this time the transfer trip pawls 116 will be urged by their springs 116 to their normal positions (Figs. 5, 6, and 7). When the high part of the cam 214 is reached continued clockwise rotation of the shaft 74 will permit the shaft 219 to be 30 restored to normal, thereby lowering the transfer pawls 120 slightly until the lugs 121 again engage the shoulders 118 of the transfer trip pawls 117. At the termination of the resetting operation the transfer mechanism is again in the 35 position shown in Fig. 7, permitting transferring to be performed in the regular manner and at the end of this operation the resetting key is withdrawn from the machine.

40 The nature of the improved mechanism is such that in order to make the foregoing description as clear as possible, it was necessary to state the operation considerably in detail as an incident to explaining the various features of construction, and a complete re-statement of operation here is 45 believed to be unnecessary.

Although the transfer mechanism and cooperating parts have been shown in connection with a particular type of cash register it is readily evident that they may be applied to other 50 forms of cash registers or adding machines.

While the form of mechanism herein shown and described is admirably adapted to fulfill the objects primarily stated it is to be understood that this embodiment is merely illustrative, since the 55 invention is susceptible of embodiment in various other forms all coming within the scope of the claims which follow:

I claim:

1. In a machine of the class described, a plurality of totalizer elements of denominational orders, a transfer pawl controlled by an element of lower order and adapted to operate an element of higher order, a reciprocating link adapted to operate said pawl, and an oscillatable cam adapted to first idly rock said link laterally and then slide it longitudinally to effect a transfer. 60

2. In a cash register, the combination of a series of keys, a reciprocating shaft driven by the keys, transfer actuating members, cams carried by said shaft for driving the transfer actuating members, said cams when moved in one direction producing an idle movement of said members, and a tensioning device effective during movement of the cams 65 70 75

- in said one direction for restoring the transfer actuating members to their normal positions.
3. In a cash register, the combination of a series of keys, a reciprocating shaft driven by the keys, transfer actuating members, transfer cams driven by said shaft for operating the transfer actuating members, said members being given an idle movement as said shaft is turned in one direction, and a tensioning device for restoring the transfer actuating members to their normal positions, one of said cams being arranged to shift said device to an inactive position during a portion of the stroke of the keys.
4. In a cash register, the combination of a series of keys, a shaft driven by the keys, transfer actuating members, means on said shaft for rocking said members, a tensioning device for restoring the transfer actuating members to their normal positions, and a cam carried by said shaft arranged to render said device ineffective during a portion of the stroke of the keys.
5. In a cash register, the combination of a series of keys, a reciprocating shaft driven by the keys, transfer actuating members, transfer cams driven by the shaft for driving the transfer actuating members, said cams being adapted to rock said members, and a tensioning device for restoring the transfer actuating members to their normal positions when rocked, the tensioning device being normally out of contact with said members.
6. In a cash register, the combination of a series of keys, a reciprocating shaft driven by the keys, transfer actuating members, transfer cams driven by the shaft for driving the transfer actuating members, said cams serving also to idly rock said members, and a tensioning device for restoring the transfer actuating members to their normal positions, the tensioning device being normally out of contact with said members, and one of said cams being arranged to render said device ineffective during a portion of the stroke of the keys.
7. In a cash register, the combination of a plurality of totalizer elements, a transfer pawl, means for actuating said pawl upon each operation of the machine, a trip pawl normally holding said transfer pawl inactive, means carried by a lower order totalizer element adapted to rock said trip pawl to release the transfer pawl for an effective transferring operation, and a pin carried by the trip pawl adapted to contact with the upper portion of said transfer pawl when said trip pawl is tripped to positively force the transfer pawl to its effective position.

CHARLES W. GREEN.
